[57] CLAIM

The ornamental design for a motorized rope skipper, as shown and described.

DESCRIPTION

FIG. 1 is a top view of the motorized rope skipper of the present invention;

FIG. 2 is a front elevational view of the motorized rope skipper of FIG. 1, the rear elevational view being a mirror image thereof;

FIG. 3 is a left side elevational view of the motorized rope skipper of FIG. 1; and,

FIG. 4 is a right side elevational view of the motorized rope skipper of FIG. 1.

A portion of the claimed design is shown broken to indicate indeterminate length.

The bottom of the rope skipper is flat and unornamented.
